UNITED STATES PATENT OFFICE

OSWALD HAFERKORN, OF POPPITZ, NEAR ROCHLITZ, GERMANY

SWITCH RAIL FOR MONORAIL SUSPENDED RAILWAYS

Application filed March 9, 1928, Serial No. 260,405, and in Germany November 22, 1927.

This invention relates to an improved hand-operated switch rail for mono-rail suspended railways, which is upwardly turnable and laterally movable on the permanent 5 track rail and at its free end provided with a notch corresponding to a similar notch of the branch rail, which has lateral fish-plates with projecting ends thereon for guiding the switch rail, the operation of the switch rail 10 being effected by means of a separate handle having a hook thereon for engagement with the switch rail.

The accompanying drawing illustrates the improved arrangement.

15 Fig. 1 is a plan view of a railway branch with three switch rails,

Figs. 2 and 3 show the switch rail on a larger scale with the adjoining track rails, in closed and open position respectively,

20 Fig. 4 is a cross-section through a track rail,

Fig. 5 is a cross-section through the switch rail with the operating handle thereon,

Fig. 6 is a plan view partly in section of 25 the pivoted attachment of the switch rail to the track rail.

As shown in Fig. 1, the mono-rail suspended railway comprises in the example illustrated a permanent track *a* and another 30 permanent track *d* at right angles thereto, with curved branches *e* between them, which are all suspended from a support *c* by means of brackets *b* (Fig. 2), while between the branches *e* and each of the rail tracks *a*, *d* one 35 switch *f* is arranged, which consists of a rail section.

As shown in Figs. 2, 3 and 6, the switch rail *f* is at one end pivoted at *i* to fish plates *g* fixed at *h* to and projecting somewhat from 40 the end of the permanent track *d* and slightly spread apart at their freely projecting ends in such a way that the switch rail can be somewhat turned in an upward direction as well as in sidewise directions, while a lower 45 abutment *n* on the end of the permanent track prevents a movement of the switch rail in a downward direction beyond its normal level.

The free end of the switch is at its lower 50 part provided with a notch *k* corresponding to a similar notch in the end of the branch

rail *e*, which has lateral fish-plates *l* thereon fixed at *m* and projecting somewhat therefrom to serve as a guide for the free notched end of the switch rail.

The operation of the switch rail is effected 55 by means of a separate handle *o* having a hook *p* thereon adapted to be placed with its opening *q* sidewise over the switch rail, whereupon the latter can be somewhat lifted and changed from one branch rail *e* to the 60 other, or from the permanent track rail *a* to the branches *e*, as the case may be.

What I claim, is:

1. In a switch for mono-rail suspended railways and in combination with a track rail 65 and a branch rail having a free notched end, the arrangement of a switch rail pivoted to the free end of said track rail and movable thereon in upward and sidewise directions and having a free notched end, and means 70 on the said branch rail for guiding the free end of the said switch rail.

2. In a switch for mono-rail suspended railways, and in combination with a track rail and a branch rail having a free notched end, 75 the arrangement of a switch rail pivoted to the free end of said track rail and movable thereon in upward and sidewise directions, and having a free notched end, fish- 80 plates fixed to the free end of said track rail projecting somewhat therefrom and there spread apart and to which said switch rail is pivoted, and an abutment on the track rail for preventing said switch rail from moving 85 in downward direction beyond its normal level.

In testimony whereof I have hereunto set my hand.

OSWALD HAFERKORN.
